UNITED STATES PATENT OFFICE.

LOUIS RUBIN, OF PHILADELPHIA, PENNSYLVANIA.

UNDERWEAR.

Application filed February 18, 1927. Serial No. 169,214.

My invention relates to underwear and more particularly to modifications in union suits of the athletic type.

A great many men prefer to wear the short athletic underwear throughout the year but find that such undergarments do not afford sufficient protection to the chest and back, consequently making it necessary to wear an extra garment, such as a vest, or change to heavy underwear when they would much prefer the short athletic type.

The principal object of my invention is to provide underwear which will combine the comfort of the athletic type with suitable protection from cold weather.

Another object of my invention is to provide garments that may be laundered in the same manner as ordinary cotton goods without danger of being distorted by shrinking. These objects, and other advantageous ends which will be described hereinafter, I attain in the following manner, reference being had to the accompanying drawings in which

Figure 1 is a front view of a suit of underwear embodying my invention;

Figure 2 a vertical section taken on line 2—2 on Figure 1, and

Figure 3 a transverse section taken on line 3—3 on Figure 1.

Figure 4 is a front view of a suit of underwear showing a certain modification of my invention, and

Figure 5 a vertical section taken on line 5—5 on Figure 4 and showing an additional modification.

Referring now more particularly to Figures 1, 2 and 3, the main garment 6 is a union suit made in the same manner as is customary in the manufacture of the athletic type of cotton underwear and may be made of similar material. Superimposed on the upper part of main garment 6 is a vest comprising a front piece 7 and a back piece 8 secured to one another by seams on the tops of the shoulders 9 and by seams extending from the arm holes to the bottom of the vest. The front and back pieces are stitched to the main garment at these points as well as around the neck 10, around arm holes 11, along front edges 12 and 13, and across the bottom 14 of the vest.

The union suit shown opens down the front and edges 12 and 13 are secured to one another by a series of buttons 15 and a knitted webbing 16 is inserted in the back of

main garment 6; both these features being customary in athletic underwear. Back piece 8 extends from the top of the shoulder to the point where webbing 16 is usually attached and front piece 7 extends down the front of the garment to a point approximately opposite the lower edge of piece 8.

As athletic underwear is provided with large loose arm holes, I provide an elastic band 17 which has its ends stitched in seam 18 forming the bottom of arm hole 11. The normal length of elastic 17 is considerably shorter than the distance between the points on seam 18 to which its ends are attached so that gathers 19 are formed in seam 18, as plainly shown in Figure 3.

By referring to Figure 1, it will be noted that pieces 7 and 8 are cut away from the bottom of the arm hole 11 so that a small portion of the material forming main garment 6 is exposed. In other words, the arm hole formed in the vest is larger than the arm hole formed in the main garment. This is done in order that free movement may be provided for the wearer of the garment, as pieces 7 and 8 are preferably made of knitted worsted material fully pre-shrunk and are intended to cause the upper part of the garment to fit snugly. Clinging to the body in this manner, the material forming seam 18 would tend to flare outwardly and elastic 17 is provided to bring this material against the body.

The garment illustrated in Figures 4 and 5 is similar in all respects to the garment illustrated in Figure 1 with the exception that front piece 7^a is much longer than piece 7 so that it will extend below the waist of the wearer. The lower end of piece 7^a is somewhat pointed, as shown in Figure 4, in order that there will be no excess material to encumber the wearer when bending or sitting. This piece is preferably the full width of the garment at a point approximately at the top of the hips of the wearer and curves downwardly from each edge to a point well below the waist line.

In Figure 5, I have shown an elastic webbing 16^a made from knitted worsted material in place of the thin cotton webbing 16 usually employed in athletic underwear in order to provide protection to the wearer at this point. I have shown piece 16^a disposed between main garment 6 and piece 8 in order to more clearly illustrate that piece 16^a is different from piece 16 but it is readily

understood that this piece may be attached to the garment in the same manner as is piece 16 or in any other manner desired. With the exception of front piece 7^a and 5 webbing 16^a, all parts are duplicates of those shown in Figures 1, 2 and 3 and have been given like reference numerals.

In manufacturing the garment, any of the customary materials are employed in the 10 manufacture of main garment 6 but, for pieces 7 and 8, I preferably employ a closely knitted worsted elastic cloth which has been thoroughly pre-shrunk so that the completed garment may be laundered without danger 15 of the worsted part shrinking and distorting the proportions of the garment. It is understood, of course, that heavy weight cotton or other material could readily be used in place of worsted goods but the principal object of my invention is to provide 20 a neat, well-fitting, and comfortable garment for use during the winter months. I also find that the material used by me in the

making of pieces 7 and 8 is suitable for piece 16^a as it possesses sufficient elasticity. 25

While I have described my invention as taking a particular form, it will be understood that modifications may be made without departing from the spirit therof, and hence I do not limit myself to the precise 30 construction set forth, but consider that I am at liberty to make such changes and alterations as fairly come within the scope of the appended claim.

I claim:—

A union suit including a sleeveless main garment made of woven material and having arm holes; a vest of knitted material, having arm holes larger than those in the main garment, secured to the upper part of the 40 main garment; and an elastic band secured in the lower part of each armhole in the main garment.

In testimony whereof I have signed my name to this specification.

LOUIS RUBIN.
